dimethylene, trimethylene). Representative of such cycloalkyl groups include cyclobutyl, cyclobutylmethyl, cyclobutylethyl, cyclopentyl, cyclopentylmethyl, cyclobutylpropyl, cyclohexyl, cyclohexylmethyl, cyclohexylethyl, cycloheptyl, cyclopropyl, etc.

It has been found that compounds of the foregoing type have a wide range of antibiotic or antibacterial activity against, for example, Gram-positive and Gram-negative micro-organisms.

Representative of preferred R_1 groups include dioxanyl, 2-furyl, 3-furyl, imidazolyl, isoxazolyl, morpholinyl, oxazolyl, pyranyl, pyrazinyl, pyrazolyl, N-pyridyl, 3-pyridyl, 2-pyridyl, pyrimidyl, N-pyrryl, 2-pyrryl, 3-pyrryl, thiazolyl, 2-thienyl, 3-thienyl, 2-benzothienyl, 3-benzothienyl, triazinyl, triazolyl and the like; the partially and completely hydrogenated derivatives of the foregoing, such as tetrahydrofuryl, imidazolinyl, imidazolidyl, piperidyl, tetrahydropyrimidyl, pyrrolidyl and the like; as well as all of the foregoing groups which are substituted by one or more substituents including, for example, C_1 to C_3 alkyl (e.g., methyl, ethyl, propyl, isopropyl), C_1 to C_3 alkoxy (e.g., methoxy, ethoxy, propoxy, etc.), a cyano group, a nitro group, a hydroxy group, halogen (e.g., chlorine, fluorine, bromine and iodine), a trifluoromethyl group, a carboxy group, an amino group, a C_1 to C_4 carboxyalkyl group (e.g., carboxymethyl, carboxypropyl, carboxyethyl, etc.) or a C_1 to C_4 carboxamidoalkyl group [$H_2N-C(O)-alkyl$] (e.g., carboxamidomethyl, carboxamidoethyl, etc.), as represented by the picolyls, methylfurys, methyl thiens, nitrofuryl, cyanofuryl, nitrobenzothienyl, nitropyridyl, cyanopyridyl, methoxypyrimidyl, bromopyridyl, trifluoromethylpyridyl as well as others of the type described in Flynn U.S. Pat. No. 3,218,318.

For convenience, compounds of the present invention are named by the use of the "cephem" nomenclature system. "Penam" nomenclature for the penicillins is described by Sheehan, Henery-Logan, and Johnson in the Journal of the American Chemical Society (JACS), 75, 3292, footnote 2 (1953), and has been adapted to the cephalosporins by Morin, Jackson, Flynn and Roeske [JACS, 84, 3400 (1962)]. In accordance with these systems of nomenclature "penam" and "cepham" refer respectively to the following saturated ring systems:

"Penam" (VII)

"Cepham" (VIII)

"Cephem" refers to the cepham ring construction containing a double bond, the position of which is indicated by a prefixed " Δ " with a superscript denoting the lowest numbered carbon atom to which the double bond is connected, or by the word "delta" with the same number relationship. Thus, for example, penicillin V, 6-phenoxy-methylpenicillin, can be named 6-(phenoxyacetamido)-2,2-dimethyl-penam-3-carboxylic acid, and 7-phenoxyacetamido desacetoxycephalosporanic acid can be named as 7-phenoxyacetamido-3-methyl- Δ^3 -cephem-4-carboxylic acid. Sometimes the position of the double bond is indicated merely by the integer before the word "cephem."

One of the most preferred compounds of the present invention

(IX)

can be named 7-(2'-thienylacetamido)-3-cyclobutylcarbonyloxymethyl- Δ^3 -cephem-4-carboxylic acid.

Illustrative of the preferred compounds of this invention include the following:

- 5 7-(2'-pyranylacetamido)-3-cyclobutylcarbonyloxymethyl- Δ^3 -cephem-4-carboxylic acid
 7-(3'-pyranylacetamido)-3-cyclohexylacetoxymethyl- Δ^3 -cephem-4-carboxylic acid
 10 7-(2'-piperidylacetamido)-3-cyclohexylcarbonyloxy-
 methyl- Δ^3 -cephem-4-carboxylic acid
 7-(2'-piperidylacetamido)-3-cyclobutylcarbonyloxy-
 methyl- Δ^3 -cephem-4-carboxylic acid
 15 7-(2'-pyridylacetamido)-3-cyclobutylcarbonyloxymethyl- Δ^3 -cephem-4-carboxylic acid sodium salt
 7-(2'-pyridylacetamido)-3-cyclohexylacetoxymethyl- Δ^3 -cephem-4-carboxylic acid
 7-(5'-oxazolylacetamido)-3-cyclopentylacetoxymethyl- Δ^3 -cephem-4-carboxylic acid
 20 7-(5'-oxazolylacetamido)-3-cyclopentylpropionoxy-
 methyl- Δ^3 -cephem-4-carboxylic acid
 7-(4'(5')imidazolylacetamido)-3-cyclobutylcarbonyl-
 oxymethyl- Δ^3 -cephem-4-carboxylic acid
 7-(2'-morpholinylacetamido)-3-cyclobutylacetoxymethyl- Δ^3 -cephem-4-carboxylic acid
 25 7-(2'-morpholinylacetamido)-3-cyclobutylacetoxymethyl- Δ^3 -cephem-4-carboxylic acid sodium salt
 7-(2'-pyrazenylacetamido)-3-cyclohexylcarbonyloxy-
 methyl- Δ^3 -cephem-4-carboxylic acid
 30 7-(5'-imidoazolinyacetamido)-3-cyclohexylpropion-
 oxymethyl- Δ^3 -cephem-4-carboxylic acid
 7-(5'-imidoazolinyacetamido)-3-cyclohexylacetoxymethyl- Δ^3 -cephem-4-carboxylic acid
 7-(2'-thienylacetamido)-3-cyclobutylacetoxymethyl- Δ^3 -
 35 7-(2'-thienylacetamido)-3-cyclobutylacetoxymethyl- Δ^3 -cephem-4-carboxylic acid potassium salt
 7-(3'-bromo-2'-pyridylacetamido)-3-cyclohexylcarbonyl-
 oxymethyl- Δ^3 -cephem-4-carboxylic acid
 7-(3'-bromo-2'-pyridylacetamido)-3-cyclobutylcarbonyl-
 oxymethyl- Δ^3 -cephem-4-carboxylic acid
 40 7-(5'-fluoro-2'-pyridylpropionacetamido)-3-cyclopentyl-
 propionoxymethyl- Δ^3 -cephem-4-carboxylic acid
 7-(5'-pyrimidylpropionacetamido)-3-cyclobutylcar-
 bonyloxymethyl- Δ^3 -cephem-4-carboxylic acid potassium
 45 7-(5'-pyrimidylpropionacetamido)-3-cyclopentaneace-
 toxymethyl- Δ^3 -cephem-4-carboxylic acid
 7-(5'-nitro-2'-thienylacetamido)-3-cyclopentylpropion-
 oxymethyl- Δ^3 -cephem-4-carboxylic acid
 7-(5'-nitro-2'-thienylacetamido)-3-cyclopentanoyloxy-
 methyl- Δ^3 -cephem-4-carboxylic acid potassium salt
 50 7-(2'-furylbutyrylacetamido)-3-cyclobutylcarbonyloxy-
 methyl- Δ^3 -cephem-4-carboxylic acid
 7-(2'-thiazolylacetamido)-3-cyclohexylcarbonyloxy-
 methyl- Δ^3 -cephem-4-carboxylic acid
 55 7-(2'-thienylvaleramido)-3-cyclopentylpropionoxymeth-
 yl- Δ^3 -cephem-4-carboxylic acid
 7-(3'-thienylhexanoylamido)-3-cyclopentylcarbonyl-
 oxymethyl- Δ^3 -cephem-4-carboxylic acid
 7-(α -picolyl-3'-acetamido)-3-cyclobutylcarbonyloxy-
 methyl- Δ^3 -cephem-4-carboxylic acid
 60 7-(2'-thienylpropionamido)-3-cyclopropylcarbonyloxy-
 methyl- Δ^3 -cephem-4-carboxylic acid
 7-(2'-thienylpropionamido)-3-cyclopropylcarbonyloxy-
 methyl- Δ^3 -cephem-4-carboxylic acid
 65 7-(2'-methyl-3'-furylacetamido)-3-cyclobutylpropion-
 oxymethyl- Δ^3 -cephem-4-carboxylic acid
 7-(2'-furyl-n-butylamido)-3-cyclopentylpropionoxy-
 methyl- Δ^3 -cephem-4-carboxylic acid
 70 7-(2'-furyl-n-butylamido)-3-cyclohexylacetoxymethyl-
 Δ^3 -cephem-4-carboxylic acid
 7-(2'-triazinylacetamido)-3-cyclopentaneacetoxymethyl-
 Δ^3 -cephem-4-carboxylic acid
 7-(5'-methoxy-3'-pyridylacetamido)-3-cyclohexylace-
 toxymethyl- Δ^3 -cephem-4-carboxylic acid

7-(5'-methoxy-3'-pyridylacetamido)-3-cyclopropylcarbonyloxymethyl- Δ^3 -cephem-4-carboxylic acid
7-(2'-triazinylacetamido)-3-cyclohexylpropionoxy-methyl- Δ^3 -cephem-4-carboxylic acid.

As is the case with the penicillins to which the compounds of this invention are related in some degree, numerous salts, esters, amides and like derivatives thereof can be prepared by combination with non-toxic pharmaceutically acceptable cations, alcohols, ammonia and amines. Such derivatives can be regarded as equivalent to the compounds disclosed, and are included within the scope of the present invention.

For purposes of illustration, there can be mentioned several types of cationic salts which can be prepared from compounds of Formula VI including for example, water-soluble salts such as the sodium, potassium, lithium, ammonium and substituted ammonium salts, as well as the less water-soluble salts such as the calcium, barium, procaine, quinine and dibenzylethylenediamine salts.

Another concept of the invention resides in a new and improved process which represents a heretofore unavailable, key chemical procedure making it possible to prepare the novel compounds described above. It has been found in accordance with the practice of the process of this invention that a 7-acylamido-3-acyloxymethyl- Δ^2 -cephalosporin having the formula

wherein R_a is the residue of the acylamido group in the 7-position, R_4 is hydrogen or the residue of an ester forming alcohol and R_3 is a C_1 to C_7 alkyl group (e.g., methyl, ethyl, propyl, isopropyl, butyl, isobutyl, etc.) or a cycloalkyl group

wherein R_2 and m are defined above, can be prepared by reacting a 7-acylamido desacetylcephalosporin compound with an anhydride of a saturated aliphatic carboxylic acid.

As the desacetylcephalosporin compound, use is made of a 7-acylamido- Δ^2 -desacetylcephalosporin of the formula

wherein R_a and R_4 are as defined above.

As the acid anhydride, use can be made of any of the aliphatic carboxylic acid anhydrides containing 4-20 carbon atoms. Preferred anhydrides are those having the general formula

wherein R_5 is an alkyl group containing 1-7 carbon atoms, such as methyl, ethyl, propyl, isopropyl, butyl, isobutyl, pentyl, hexyl, heptyl, etc., or a cycloalkyl having the formula

wherein R_2 is C_1 to C_5 alkylene (i.e., methylene, dimethylene, trimethylene) and m is zero or an integer from 1 to 4. Representative of the foregoing cycloalkyl groups include cyclobutyl, cyclobutylmethyl, cyclobutylethyl, cyclo-

pentyl, cyclopentylethyl, cyclopentylmethyl, cyclohexyl, cyclohexylmethyl, cyclopropyl, cyclopropylmethyl, etc.

Illustrative of the carboxylic acid anhydrides which can be employed in accordance with the practice of the process of this invention include acetic anhydride, propionic anhydride, butyric anhydride, isobutyric anhydride, pentanoic anhydride, hexanoic anhydride, heptanoic anhydride, cyclobutane carboxylic anhydride, cyclopentane carboxylic anhydride, cyclohexane carboxylic anhydride, cyclobutaneacetic anhydride, cyclobutanepropionic anhydride, cyclopentaneacetic anhydride, cyclohexaneacetic anhydride, cycloheptaneacetic anhydride, cyclohexanepropionic anhydride, etc.

The reaction between the anhydride and the desacetylcephalosporin is preferably carried out in the presence of an organic base. Any of a variety of organic bases can be used for this purpose. Preferred organic bases are the secondary and tertiary amines having a pK_a less than 8. Representative of suitable bases are diethyl amine, triethyl amine, pyridine, piperidine, morpholine as well as a number of others known to those skilled in the art.

If desired, the reaction can be carried out in the presence of an inert organic solvent. However, since the organic base is generally a liquid under normal conditions, it is usually preferred to operate without a solvent, using the organic base as the solvent.

The reaction temperature is not critical, and can be varied within wide ranges. In general, use should be made of a reaction temperature within the range of -10 to 100°C., and preferably 0° to 30°C.

The 7-acylamido group, and the residue of the ester forming alcohol (R_4) when use is made of a starting material in the form of an ester, do not enter into the reaction, and thus the nature of these groups does not affect the nature of the reaction. For this reason, the 7-acylamido group and the R_4 group (when the latter is other than hydrogen) can be any of a number of groups which are now well recognized by those skilled in the penicillin and cephalosporin arts.

Illustrative of suitable acyl groups which can be present in the starting materials employed in accordance with the practice of the invention include those acyl groups having the formula

wherein n is zero or an integer from 1 to 6 and R_6 is an organic group such as $HOOC-CH(NH_2)-(CH_3)_3$ or an aryl group or a substituted aryl group containing 6-14 carbon atoms.

Preferred aryl groups are those derived from benzene or naphthalene

wherein Q is hydrogen or one or more substituents including, for example, C_1 to C_3 alkyl (e.g., methyl, ethyl, propyl, isopropyl), C_1 to C_3 alkoxy (e.g., methoxy, ethoxy, propoxy, etc.), a cyano group, a nitro group, a hydroxy group, halogen (e.g., chlorine, fluorine, bromine and iodine), a trifluoromethyl group, a carboxy group, an amino group, a C_1 to C_4 carboxyalkyl group (e.g., carboxymethyl, carboxyethyl, carboxypropyl, etc.), or a C_1 to C_4 carboxamidoalkyl group [$H_2N-C(O)-alkyl$] (e.g., carboxamidomethyl, carboxamidoethyl, etc.).

Representative acyl groups are 5-amino adipoyl, benzoyl, phenylacetyl, beta-(phenyl)propionyl, naphthoyl, naphthylacetyl, gamma-phenylbutyryl, p-methylbenzoyl, 2,4-dimethylphenylacetyl, 5-methoxynaphthylacetyl, p-cyanophenylacetyl, 4-nitronaphthoyl, 3-nitrobenzoyl, 3,5-dicyanophenylacetyl, beta-(3-nitrophenyl)-propionyl, p-hydroxybenzoyl, 4-hydroxyphenylacetyl, p-chlorophenylacetyl, m-bromobenzoyl, 3-trifluoromethylphenylacetyl,

o-carboxyphenylacetyl, m-carboxymethylphenylacetyl, m-carboxamidomethylphenylacetyl, beta(5 - carboxamido-methylnaphthyl)propionyl, aminobenzoyl, aminophenylacetyl as well as a number of others.

R_6 can also be a cycloalkyl group containing 4-8 carbon atoms, including cyclobutyl, cyclopentyl, cyclohexyl, cycloheptyl, etc. In addition, R_6 can also be one of the foregoing cycloalkyl groups which is substituted by one or more of the Q substituents described above.

Illustrative of such acyl groups include cyclopentanoyl, 10 cyclohexanoyl, 3 - methylcyclohexanoyl, cyclobutylcarbonyl, 2 - methoxycyclohexanoyl, 3-chlorocyclohexyl-acetyl, cyclopentylacetyl, beta-cyclopentylpropionyl, 3-methoxycyclohexylacetyl, 2-cyanocyclopentylacetyl, 3-nitrocyclohexanoyl, 3 - carboxycyclohexylacetyl, 3-carboxyamidomethylcyclohexylacetyl, etc.

R_6 can also be a heterocyclic group wherein the hetero-atom is O, S, N or any combination thereof, including dioxanyl, 2 - furyl, 3-furyl, imidazolyl, isoxazolyl, morpholinyl, oxazolyl, pyranyl, pyrazinyl, pyrazolyl, N-pyridyl, 2 - pyridyl, 3-pyridyl, pyridimidyl, N-pyrryl, 2-pyrryl, 3-pyrryl, thiazolyl, 2-thienyl, 3-thienyl, 2-benzothienyl, 3-benzothienyl, triazinyl, triazolyl and the like; the partially and completely hydrogenated derivatives of the foregoing, such as tetrahydrofuryl, imidazolinyl, imidazolidyl, piperidyl, tetrahydropyrimidyl, pyrrolidyl and the like; as well as all of the foregoing group which are substituted by one or more of the Q groups described above, as represented by the picolyls, methylfuryls, methyl thiens, nitrofuryl, cyanofuryl, nitrobenzothienyl, nitropyridyl, cyanopyridyl, methoxypyrimidyl, bromopyridyl, trifluoromethylpyridyl as well as others of the type described in Flynn U.S. Pat. No. 3,218,318.

Illustrative of acyl groups when R_6 is heterocyclic are dioxanylacetyl, 2-furylcarbonyl, beta-pyrazinylpropionyl, 35 2 - pyridylacetyl, 3-pyridylcarbonyl, 2-thienylacetyl, 3-benzothienylcarbonyl, piperidylacetyl, pyrrolidylcarbonyl, nitrobenzothienylacetyl, beta-(nitrofuryl)-propionyl, cyanopyridylcarbonyl, etc.

The acyl group forming the 7-acylamido group can further be an acyl group having the general formula

wherein R_7 is either alkyl containing 1-8 carbon atoms (e.g., methyl, ethyl, isopropyl, n-butyl, tert-butyl, hexyl, isooctyl, etc.) or alkenyl containing 2-8 carbon atoms (e.g., vinyl, allyl, 2-butenyl, 3-hexenyl, etc.). R_7 can also be one of the foregoing alkyl or alkenyl groups which is substituted by one or more substituents including, for example, an amino group, a cyano group, a nitro group, a hydroxy group, halogen (e.g., chlorine, fluorine, bromine, iodine), a carboxy group or a carboxamide group

Illustrative of these acyl groups are acetyl, propionyl, acrylyl, crotoyl, 2 - aminoacetyl, 3-chloropropionyl, 6-heptenoyl, adipoyl, 3-hydroxypropionyl and 5-nitrohexanoyl.

Also included within the scope of the invention are those desacetylcephalosporin compounds wherein R is an acyl group having the formula

wherein n is as previously described, m is zero or an integer from 1 to 5, X is O or S and R_8 is R_6 (i.e., aryl, cycloalkyl or heterocyclic) as described above including substituted derivatives thereof, or R_7 (i.e., C_1 to C_8 alkyl or C_3 to C_8 alkenyl) as described above, including substituted derivatives thereof.

Representative of the acyl groups defined by (XX) above include tert-butoxycarbonyl, tert-butoxyacetyl, ethoxyacetyl, tert-butylmercaptocarbonyl, tert-butylmercaptoacetyl, allylmercaptoacetyl, 3 - bromopropoxyacetyl,

3 - hydroxypropylcarbonyl, 2-thienyloxyacetyl, piperidyl-mercaptoproacetyl, 2 - pyridyloxycarbonyl, phenoxyacetyl, naphthoxyacetyl, phenoxyacetyl, aminophenoxyacetyl, beta-(phenoxy)-propionyl, cyclohexyloxyacetyl, chlorocyclopentyloxyacetyl, benzylacetyl, phenylmercaptoacetyl, phenylbutoxyacetyl, phenylethylmercaptoacetyl and phenylmercaptoacetyl as well as a wide variety of others.

The 7-acyl group can further be an acyl group having the general formula

wherein Y is an amino group, a protected amino group, hydroxy, C_1 to C_3 alkoxy (e.g., methoxy, ethoxy, etc.) carboxyl or C_1 to C_3 alkanoyloxy (e.g., acetoxy, propionoxy, etc.) and R_9 is one of the groups defined by R_6 above (i.e., aryl, heterocyclic and cycloalkyl as described in detail above).

Representative of the foregoing acyl groups are 2-phenyl - 2-aminoacetyl, 2-(p-methoxyphenyl)-2-aminoacetyl, 2-cyclohexyl-2-methoxyacetyl, 2-phenyl-2-acetoxyacetyl, 2-(2' - pyridyl)-2-hydroxyacetyl, 2-piperidyl-2-aminoacetyl, 2 - (2'-thienyl)-2-acetoxyacetyl as well as a variety of others.

In addition to the foregoing, R can be a number of other acyl groups, including, for example, phenyl-a,a-dimethylacetyl and Q substituted derivatives thereof and a number of others. Various other suitable R acyl groups are disclosed in the Behrens et al. U.S. Pats. Nos. 2,479,-295, 2,479,297, 2,562,407 and 2,623,876.

As will be appreciated by those skilled in the art, when the 7 - acylamido group contains an unprotected amino group, such amino group may be acylated by the anhydride employed. However, this is not disadvantageous since the 7-acylamido group can easily be removed to form the corresponding 7-amino compound and reacylated as desired.

As indicated above, when use is made of an ester starting material, the nature of the reaction is not significantly affected by the nature of the ester protecting group or residue R_4 . It is generally preferred that R_4 be an ester residue which is easily cleaved by known means, such as by dilute aqueous base, trifluoroacetic acid or by hydrogenation in the presence of a palladium or rhodium catalyst on a suitable carrier such as carbon, barium sulfate or alumina so that the cephalosporin is not degraded, since the ultimate product is generally used in the form of the acid.

Representative R_4 groups include C_4 to C_6 tertiary alkyl (e.g., tert-butyl, tert-pentyl, etc.), C_5 to C_7 tertiary alkenyl (e.g., tert-pentenyl, tert-hexenyl, etc.), C_5 to C_7 tertiary alkynyl (e.g., 1,1-dimethyl-2-pentynyl, etc.), benzyl, methoxybenzyl, phenyl, methoxyphenyl, nitrobenzyl, phenacyl, trichloroethyl, trimethylsilyl, benzhydryl, phthalimidomethyl, succinimidomethyl as well as a number of others apparent to those skilled in the art.

Examples of the Δ^2 -desacetylcephalosporin acids and esters which can be used as the starting material in the practice of this invention include the following.

- 7-(5'-carboxy-5'-valeramido)-3-hydroxymethyl- Δ^2 -cephem-4-carboxylic acid
- 7-phenoxyacetamido-3-hydroxymethyl- Δ^2 -cephem-4-carboxylic acid
- 7-phenylacetamido-3-hydroxymethyl- Δ^2 -cephem-4-carboxylic acid
- B₂B₂B-trichloroethyl 7-phenylmercaptoacetamido-3-hydroxymethyl- Δ^2 -cephem-4-carboxylate
- 7-benzoyloxyacetamido-3-hydroxymethyl- Δ^2 -cephem-4-carboxylic acid
- tert-butyl 7-(4'-methylphenylbutyrylamido)-3-hydroxymethyl- Δ^2 -cephem-4-carboxylate
- 7-(4'-propylbenzylmercaptoacetamido)-3-hydroxymethyl- Δ^2 -cephem-4-carboxylic acid

- 1,1-dimethyl-2-pentynyl 7-(4'-propylbenzyl-mercaptopacetamido)-3-hydroxymethyl- Δ^2 -cephem-4-carboxylate
 7-benzylmercaptopropionamido-3-hydroxymethyl- Δ^2 -cephem-4-carboxylic acid
 7-phenylpropionamido-3-hydroxymethyl- Δ^2 -cephem-4-carboxylic acid
 tert-butyl 7-phenylethylmercaptopropionamido-3-hydroxymethyl- Δ^2 -cephem-4-carboxylate
 7-phenylethylmercaptopropionamido-3-hydroxymethyl- Δ^2 -cephem-4-carboxylic acid
 tert-butyl 7-phenylbutoxybutyrylamido-3-hydroxymethyl- Δ^2 -cephem-4-carboxylic acid
 7-phenylbutoxybutyrylamido-3-hydroxymethyl- Δ^2 -cephem-4-carboxylic acid
 benzyl 7-phenylbutoxybutyrylamido-3-hydroxymethyl- Δ^2 -cephem-4-carboxylate
 7-(3'-fluorophenoxyacetamido)-3-hydroxymethyl- Δ^2 -cephem-4-carboxylic acid
 trimethylsilyl 7-(4'-bromophenylacetamido)-3-hydroxymethyl- Δ^2 -cephem-4-carboxylate
 7-phenyl-a,a-dimethylacetamido-3-hydroxymethyl- Δ^2 -cephem-4-carboxylic acid
 p-nitrobenzyl 7-phenyl-a,a-dimethylacetamido-3-hydroxymethyl- Δ^2 -cephem-4-carboxylate
 p-methoxybenzyl 7-(2'-chlorobenzylxypropionamido)-3-hydroxymethyl- Δ^2 -cephem-4-carboxylate
 tert-butyl 7-benzamido-3-hydroxymethyl- Δ^2 -cephem-4-carboxylate
 p-nitrobenzyl 7-phenylacetamido-3-hydroxymethyl- Δ^2 -cephem-4-carboxylate
 7-(4'-nitrophenylmercaptoacetamido)-3-hydroxymethyl- Δ^2 -cephem-4-carboxylic acid
 7-(3'-cyanophenylpropionamido)-3-hydroxymethyl- Δ^2 -cephem-4-carboxylic acid
 7-(3'-trifluoromethylphenoxyacetamido)-3-hydroxymethyl- Δ^2 -cephem-4-carboxylic acid
 7-butryrylamido-3-hydroxymethyl- Δ^2 -cephem-4-carboxylic acid
 tert-butyl 7-cyclohexylacetamido-3-hydroxymethyl- Δ^2 -cephem-4-carboxylate
 7-cyclohexylacetamido-3-hydroxymethyl- Δ^2 -cephem-4-carboxylic acid
 succinimidomethyl 7-(beta-aminopropionamido)-3-hydroxymethyl- Δ^2 -cephem-4-carboxylate
 7-allylmercaptoacetamido-3-hydroxymethyl- Δ^2 -cephem-4-carboxylic acid
 p-methoxybenzyl 7-allylmercaptoacetamido-3-hydroxymethyl- Δ^2 -cephem-4-carboxylate
 7-(gamma-chlorocrotylmercaptoacetamido)-3-hydroxymethyl- Δ^2 -cephem-4-carboxylic acid
 tert-butyl 7-(5'-amino-5'-carboxyvaleramido)-3-hydroxymethyl- Δ^2 -cephem-4-carboxylate
 7-(5'-amino-5'-carboxyvaleramido)-3-hydroxymethyl- Δ^2 -cephem-4-carboxylic acid
 7-(2'-thienylacetamido)-3-hydroxymethyl- Δ^2 -cephem-4-carboxylic acid
 B,B,B-trichloroethyl 7-(2'-thienylacetamido)-3-hydroxymethyl- Δ^2 -cephem-4-carboxylate
 7-(n-butylmercaptoacetamido)-3-hydroxymethyl- Δ^2 -cephem-4-carboxylic acid
 p-nitrobenzyl 7-(tert-butoxyacetamido)-3-hydroxymethyl- Δ^2 -cephem-4-carboxylate
 7-tert-butoxyacetamido)-3-hydroxymethyl- Δ^2 -cephem-4-carboxylic acid
 benzyl 7-(2'-benzothienylacetamido)-3-hydroxymethyl- Δ^2 -cephem-4-carboxylate
 7-(3'-pyridylacetamido)-3-hydroxymethyl- Δ^2 -cephem-4-carboxylic acid
 7-(2'-pyranylacetamido)-3-hydroxymethyl- Δ^2 -cephem-4-carboxylic acid
 7-(5'-oxazolylacetamido)-3-hydroxymethyl- Δ^2 -cephem-4-carboxylic acid
 tert-butyl 7-(5'-oxazolylacetamido)-3-hydroxymethyl- Δ^2 -cephem-4-carboxylate

- 7-(2'-pyrazinylacetamido)-3-hydroxymethyl- Δ^2 -cephem-4-carboxylic acid
 benzyl 7-(2'-pyrazinylacetamido)-3-hydroxymethyl- Δ^2 -cephem-4-carboxylate
 5 7-(5'-fluoro-2'-pyridylpropionamido)-3-hydroxymethyl- Δ^2 -cephem-4-carboxylic acid
 benzyl 7-(2'-furoylamido)-3-hydroxymethyl- Δ^2 -cephem-4-carboxylate
 7-(2'-furylacetamido)-3-hydroxymethyl- Δ^2 -cephem-4-carboxylic acid
 10 benzyl 7-(2'-furylacetamido)-3-hydroxymethyl- Δ^2 -cephem-4-carboxylic acid
 7-(5'-nitro-2'-thienylpropionamido)-3-hydroxymethyl- Δ^2 -cephem-4-carboxylic acid
 15 7-(5'-methoxy-3'-pyridylacetamido)-3-hydroxymethyl- Δ^2 -cephem-4-carboxylic acid.

The starting materials used in accordance with the process of this invention can be prepared by a number with citrus esterase to form desacetylcephalosporin C which can then be esterified and isomerized as illustrated below:

25

35

40

(XXII)

45

50

Esterification

55

60

Isomerization

65

wherein R' is the residue of the ester.

The product (XXIV) can then be reacted in accordance with the process of this invention.

Alternatively, the Δ^2 -desacetylcephalosporin starting material can be prepared by simultaneous hydrolysis and isomerization of the corresponding Δ^3 -cephalosporanic acid derivative using the procedure of Cocker et al., J. Chem. Soc., sect. C, 1142 (1966).

For example, cephalothin prepared in accordance with the procedure of Flynn in the aforementioned U.S. patent

75

11

can be hydrolyzed and isomerized to the corresponding Δ^2 -desacetylcephalosporin as follows

When it is desired to make use of the corresponding ester as the starting material, the product of (XXXV) can be esterified to form the corresponding 4-carboxylate in a conventional manner.

The products of the process of the present invention can be converted to the new and improved antibiotics described above as well as known antibiotics by the successive steps of oxidation and reduction. Thus,

The oxidation reaction of (XXVI) above can be carried out by, for example, the procedure described in copending application Ser. No. 764,939, filed Oct. 3, 1968, wherein description is made of the use of oxidizing agents such as per-acids (e.g., peracetic acid, metachloroperbenzoic acid, etc.) for oxidizing Δ^2 -cephem compounds to the corresponding Δ^3 -cephem sulfoxides.

Similarly, the reduction reaction of (XXVII) above can be carried out by the use of any of a number of reducing agents, such as stannous chloride, zinc chloride or sodium dithionite, in conjunction with an acid halide activator (e.g., acetyl chloride) as described in copending application Ser. No. 764,925, filed Oct. 3, 1968.

It is intended that the 7-acylamido group of the products of the process of the present invention may be removed and replaced by another 7-acylamido group in the preparation of cephalosporin-type antibiotics. For example, the 7-acylamido group can be cleaved in accordance with the procedure described by Chauvette in copending application, Ser. No. 651,662, filed July 7, 1967, to form the corresponding 7-amino compound which can, in turn, be

12

re-acylated with, for example, a heterocyclic-containing acylating agent to prepare the novel compounds of this invention as outlined below

Having described the basic concepts of the invention, reference is now made to the following examples, which are provided by way of illustration, but not by way of limitation, of the practice of the invention.

EXAMPLE 1

Preparation of 7 - (2' - thienylacetamido) - 3 - cyclobutylcarboxyloxymethyl - Δ^2 - cephem - 4 - carboxylic acid

To a solution of 2.12 g. (mM.) of 7-(2'-thienylacetamido)-3-hydroxymethyl- Δ^2 -cephem-4-carboxylic acid 35 ml. (1 m.) of pyridine, 18 mM. of cyclobutane carboxylic anhydride are added. The mixture is then stirred for 40 minutes at room temperature, and the solution is then poured into 500 ml. of cool 2 N HCl and cooled by stirring. The pH is 1.0.

The mixture is then extracted twice with ethyl acetate and the cephalosporin acid extracted with a solution of sodium bicarbonate until the pH is 7.7. The resulting alkaline solution is acidified to a pH of 2.0 and extracted with ethyl acetate, the extract is washed with water and dried. The product is identified as 7-(2'-thienylacetamido)-3-cyclobutylcarboxyloxymethyl - Δ^2 - cephem-4-carboxylic acid.

EXAMPLE 2

Preparation of 7 - (2' - thienylacetamido) - 3 - cyclobutylcarboxyloxymethyl - Δ^3 - cephem - 1 - oxide - 4 - carboxylic acid

To a solution containing 1 mM. of 7-(2'-thienylacetamido) - 3 - cyclobutylcarboxyloxymethyl- Δ^2 -cephem-4-carboxylic acid, prepared in Example 1, 15 ml. of CHCl₃, 190 mg. (0.95 mM.) of 85% monochloroperbenzoic acid are added. The mixture is warmed slightly and precipitation commences. After stirring at room temperature for about 10 minutes, two-thirds of the solvent is evaporated and the product crystallized and filtered and recrystallized from alcohol.

The product is identified as 7-(2'-thienylacetamido)-3-cyclobutylcarboxyloxymethyl - Δ^3 - cephem-1-oxide-4-carboxylic acid.

EXAMPLE 3

Preparation of 7 - (2' - thienylacetamido) - 3 - cyclobutylcarboxyloxymethyl - Δ^3 - cephem - 4 - carboxylic acid

1 mM. of the 7-(2'-thienylacetamido)-3-cyclobutylcarboxyloxymethyl- Δ^3 -cephem-1-oxide-4-carboxylic acid pre-

13

pared in Example 2, is dissolved in 18 ml. of dimethyl formamide and 560 mg. (2.5 mM.) of stannous chloride dihydrate and 2.5 ml. of acetyl chloride are added. The mixture is stirred at 18° C. for 15 minutes, poured into 40 ml. of cold water, and extracted 3 times with 25 ml. of ethyl acetate. The combined extract is then washed with water and dried. The solvent is evaporated and the remaining oil dried in vacuo to yield a product having a melting point of 120-122° C. dec.

The product is identified as 7-(2'-thienylacetamido)-3-cyclobutylcarbonyloxymethyl- Δ^3 -cephem-4-carboxylic acid.

EXAMPLE 4

Preparation of 7-(2'-furylpropionamido)-3-cyclohexylcarbonyloxymethyl- Δ^3 -cephem-4-carboxylic acid

7-(2'-furylpropionamido)-3-hydroxymethyl- Δ^2 -cephem-4-carboxylic acid is prepared by hydrolysis of 7-(2'-furylpropionamido)cephalosporanic acid prepared in accordance with Example 2 of U.S. Pat. No. 3,218,318. The resulting 3-hydroxymethyl compound is reacted with cyclohexane carboxylic anhydride according to the procedure of Example 1 to form 7-(2'-furylpropionamido)-3-cyclohexylcarbonyloxymethyl- Δ^3 -cephem-4-carboxylic acid.

The Δ^2 -compound is then oxidized with metachloroperbenzoic acid to form the corresponding sulfoxide and then reduced with sodium dithionite in a known manner. The product is identified as 7-(2'-furylpropionamido)-3-cyclohexylcarbonyloxymethyl- Δ^3 -cephem-4-carboxylic acid.

EXAMPLE 5

Preparation of 7-(2'-furylacetamido)-3-cyclopentylcarbonyloxymethyl- Δ^3 -cephem-4-carboxylic acid

7-(2'-furylacetamido)-3-hydroxymethyl- Δ^2 -cephem-4-carboxylic acid prepared by hydrolysis of the Δ^3 cephalosporanic acid is reacted with cyclopentanecarboxylic anhydride in accordance with the procedure of Example 1. The product is identified as 7-(2'-furylacetamido)-3-cyclohexylacetoxymethyl- Δ^3 -cephem-4-carboxylic acid.

The resulting Δ^2 -compound is then oxidized with metachloroperbenzoic acid and reduced with stannous chloride to form 7-(2'-furylacetamido)-3-cyclopentylcarbonyloxymethyl- Δ^3 -cephem-4-carboxylic acid.

EXAMPLE 6

Preparation of 7-(N'-methyl-2'-pyrrolylacetamido)-3-cyclohexylacetoxymethyl- Δ^3 -cephem-4-carboxylic acid

7-(N'-methyl-2'-pyrrolylacetamido)cephalosporanic acid prepared in accordance with the method described in Example 14 of U.S. Pat. No. 3,218,318 is hydrolyzed to form the corresponding Δ^2 -desacetylcephalosporanic acid. The resulting product is 7-(N'-methyl-2'-pyrrolylacetamido)-3-hydroxymethyl- Δ^2 -cephem-4-carboxylic acid which is reacted with cyclohexylacetic anhydride in accordance with the procedure described in Example 1.

The resulting product is 7-(N'-methyl-2'-pyrrolylacetamido)-3-cyclohexylacetoxymethyl- Δ^2 -cephem-4-carboxylic acid which is oxidized and then reduced in accordance with the methods of Examples 2 and 3, respectively, to form 7-(N'-methyl-2'-pyrrolylacetamido)-3-cyclohexylacetoxymethyl- Δ^3 -cephem-4-carboxylic acid.

EXAMPLE 7

Preparation of 7-(2'-4'-dimethylthiazol-5'-acetamido)-3-cyclopentylcarbonyloxymethyl- Δ^3 -cephem-4-carboxylic acid

7-(2'-4'-dimethylthiazol-5'-acetamido)cephalosporanic acid prepared in accordance with the procedure in Example 13 of U.S. Pat. No. 3,218,318 is hydrolyzed in

14

accordance with the procedure described in Example 6 to form 7-(2'-4'-dimethylthiazol-5'-acetamido)-3-hydroxymethyl- Δ^2 -cephem-4-carboxylic acid.

This product is then reacted with cyclopentanecarboxylic anhydride in accordance with the procedure of Example 1 to form tertiary butyl 7-(2'-4'-dimethylthiazol-5'-acetamido)-3-cyclopentylcarbonyloxymethyl- Δ^2 -cephem-4-carboxylate.

This product is then oxidized and reduced in accordance with the procedure of Example 6 to form the corresponding 7-(2'-4'-dimethylthiazol-5'-acetamido)-3-cyclopentylcarbonyloxymethyl- Δ^3 -cephem-4-carboxylic acid.

EXAMPLE 8

Preparation of 7-(1'-2'-4'-triazol-1'-acetamido)-3-cyclobutylacetoxymethyl- Δ^3 -cephem-4-carboxylic acid

Using the procedure described in Example 7, 7-(1'-2'-4'-triazol-1'-acetamido)cephalosporanic acid prepared in accordance with the U.S. Pat. No. 3,218,318, is hydrolyzed to form the corresponding Δ^2 -desacetyl compound which is reacted with cyclobutylacetic anhydride in accordance with the procedure described in Example 1.

The resulting product is then oxidized and reduced to form 7-(1'-2'-4'-triazol-1'-acetamido)-3-cyclobutylacetoxymethyl- Δ^3 -cephem-4-carboxylic acid.

EXAMPLE 9

Preparation of 7-(1'-pyrazoleacetamido)-3-cyclohexylcarbonyloxymethyl- Δ^3 -cephem-4-carboxylic acid

7-(1'-pyrazoleacetamido)cephalosporanic acid is hydrolyzed in accordance with the procedure described in Example 6 to form the corresponding Δ^2 -desacetylcephalosporanic compound, which is then reacted with cyclohexane carboxylic anhydride in accordance with the procedure described in Example 1.

The product is then oxidized and reduced to convert the Δ^2 -compound to the Δ^3 -compound, and the resulting product is identified as 7-(1'-pyrazoleacetamido)-3-cyclohexylcarbonyloxymethyl- Δ^3 -cephem-4-carboxylic acid.

EXAMPLE 10

Preparation of 7-(3'-thienylacetamido)-3-cyclopentylpropionoxymethyl- Δ^3 -cephem-4-carboxylic acid potassium salt

7-(3'-thienylacetamido)-3-hydroxymethyl- Δ^2 -cephem-4-carboxylic acid prepared by hydrolysis of 7-(3'-thienylacetamido)cephalosporanic acid prepared in accordance with Example 5 of U.S. Pat. 3,218,318, is reacted with cyclopentanepropionic anhydride in accordance with the procedure described in Example 1.

The resulting product is then oxidized and reduced in accordance with the procedure described in Examples 2 and 3, respectively, to yield 7-(3'-thienylacetamido)-3-cyclopentylpropionoxymethyl- Δ^3 -cephem-4-carboxylic acid, which is, in turn, reacted with potassium acetate to form the corresponding potassium salt.

EXAMPLE 11

Preparation of 7-(2'-thienylacetamido)-3-propionoxymethyl- Δ^2 -cephem-4-carboxylic acid

To a solution of 2.12 g. (6 mM.) of 7-(2'-thienylacetamido)-3-hydroxymethyl- Δ^2 -cephem-4-carboxylic acid in 81 ml. (1 mole) of pyridine, 2.34 g. (18 mM.) of propionic anhydride are added. The mixture is then stirred 40 minutes at room temperature. Thereafter, the solution is poured into 500 ml. of cold 2 N HCl and cooled by stirring; the pH is 1.0.

The mixture is then extracted twice with ethyl acetate, and the acid extracted with a solution of sodium bicarbonate until the pH is 7.7. The alkaline solution is acidified to a pH of 2.0 and extracted with ethyl acetate, the extract being washed with water and dried. The solvent is extracted and the remaining oil triturated with

15

petroleum ether giving the powdered product (1.1 g., 44.5%) M.P. 110-113° dec.

The product is identified as 7-(2'-thienylacetamido)-3-propionoxymethyl- Δ^2 -cephem-4-carboxylic acid.

Analysis.—Calcd. for $C_{17}H_{18}N_2O_6S_2$ (percent): C, 49.74; H, 4.42; N, 6.82; S, 15.64. Found (percent): C, 49.61; H, 4.40; N, 6.63; S, 15.57.

EXAMPLE 12

Preparation of 7-(2'-thienylacetamido)-3-butyryloxy-methyl- Δ^3 -cephem-4-carboxylic acid

Using the procedure described in Example 11, butyric anhydride is reacted with 7-(2'-thienylacetamido)-3-hydroxymethyl- Δ^2 -cephem-4-carboxylic acid. After separation of the reactants from the reaction mixture, the product is identified as 7-(2'-thienylacetamido)-3-butyryloxy-methyl- Δ^2 -cephem-4-carboxylic acid.

EXAMPLE 13

Preparation of 7-(2'-thienylacetamido)-3-isobutyryloxy-methyl- Δ^2 -cephem-4-carboxylic acid

Using the procedure described in Example 1, isobutyric anhydride is reacted with 7-(2'-thienylacetamido)-3-hydroxymethyl- Δ^2 -cephem-4-carboxylic acid. After separation of the reactants from the reaction mixture, the product is identified as 7-(2'-thienylacetamido)-3-isobutyryloxy-methyl- Δ^2 -cephem-4-carboxylic acid.

EXAMPLE 14

Preparation of 7-phenoxyacetamido-3-propionoxymethyl- Δ^2 -cephem-1-carboxylic acid

7-phenoxyacetamido-3-hydroxymethyl- Δ^2 -cephem-1-carboxylic acid is reacted with propionic anhydride in accordance with the procedures of Example 1. The resulting product is identified as 7-phenoxyacetamido-3-propionoxymethyl- Δ^2 -cephem-1-carboxylic acid.

EXAMPLE 15

Preparation of 7-benzylmercaptoacetamido-3-isobutyryloxy-methyl- Δ^2 -cephem-4-carboxylic acid

7-benzylmercaptoacetamido-3-hydroxymethyl- Δ^2 -cephem-4-carboxylic acid is reacted with isobutyric anhydride in accordance with the procedures of Example 1. The product is identified as 7-benzylmercaptoacetamido-3-isobutyryloxy-methyl- Δ^2 -cephem-4-carboxylic acid.

EXAMPLES 16-23

Using the procedure described in Example 1, the following 3-acyloxymethyl- Δ^2 -compounds are prepared from the reactants as indicated.

7-phenylacetyl-3-acetoxymethyl- Δ^2 -cephem-4-carboxylic acid from acetic anhydride and 7-phenylacetethyl-3-hydroxymethyl- Δ^2 -cephem-4-carboxylic acid

7-phenylmercaptoacetamido-3-propionoxymethyl- Δ^2 -cephem-4-carboxylic acid from propionic anhydride and 7-phenylmercaptoacetamido-3-hydroxymethyl- Δ^2 -cephem-4-carboxylic acid

7-(3'-benzylmercaptoacetamido)-3-butyryloxy-methyl- Δ^2 -cephem-4-carboxylic acid from butyric anhydride and 7-(3'-benzylmercaptoacetamido)-3-hydroxymethyl- Δ^2 -cephem-4-carboxylic acid

7-cyclohexylacetamido-3-propionoxymethyl- Δ^2 -cephem-4-carboxylic acid from propionic anhydride and 7-cyclohexylacetamido-3-hydroxymethyl- Δ^2 -cephem-4-carboxylic acid

7-allylmercaptoacetamido-3-cyclopentylcarboxyloxy-methyl- Δ^2 -cephem-4-carboxylic acid from cyclopentane carboxylic anhydride and 7-allylmercaptoacetamido-3-hydroxymethyl- Δ^2 -cephem-4-carboxylic acid

B,B,B-trichloroethyl 7-(5'-carboxy-5'-propionamido-valeramido)-3-propionoxymethyl-2-cephem-4-carboxylate from propionic anhydride and B,B,B-tri-

16

chloroethyl 7-(5'-carboxy-5'-amino-valeramido)-3-hydroxymethyl- Δ^2 -cephem-4-carboxylate

p-nitrobenzyl tert-butoxyacetamido-3-cyclopentane propionoxymethyl- Δ^2 -cephem-4-carboxylate from cyclopentane propionic anhydride and p-nitrobenzyl tert-butoxyacetamido-3-hydroxymethyl- Δ^2 -cephem-4-carboxylate

7-(2'-benzothienylpropionacetamido)-3-propionoxymethyl- Δ^2 -cephem-4-carboxylic acid from propionic anhydride and 7-(2'-benzothienylpropionacetamido)-3-hydroxymethyl- Δ^2 -cephem-4-carboxylic acid.

It will be understood that various changes and modifications can be made in the details of procedure, formulation and use without departing from the spirit of the invention, especially as defined in the following claims.

I claim:

1. A process for preparing a 3-acyloxymethyl- Δ^2 -cephalosporin comprising reacting a 7-acylamido-3-hydroxymethyl- Δ^2 -cephalosporin having the formula

30 wherein R_a is the residue of the 7-acylamido group and R_4 is selected from the group consisting of hydrogen and the residue of an ester forming alcohol which can be cleaved by dilute aqueous base, by trifluoroacetic acid or by hydrogenation in the presence of a palladium or rhodium catalyst on a carrier, with the anhydride of a saturated aliphatic carboxylic acid in which the anhydride contains 4 to 20 carbon atoms in the presence of an organic base having a pK_a less than 8.

35 2. A process as defined in claim 1 wherein the anhydride is an anhydride having the formula

40 45 wherein R_5 is selected from the group consisting of C_1 to C_7 alkyl and cycloalkyl having the structure

50 55 wherein n is zero or an integer from 1 to 5 and R_2 is alkylene containing 1-5 carbon atoms.

3. A process as defined in claim 1 wherein the organic base is pyridine.

4. A process as defined in claim 1 wherein R_4 is selected from the group consisting of hydrogen, C_4 to C_6 tertiary alkyl, C_5 to C_7 tertiary alkenyl, C_5 to C_7 tertiary alkynyl, benzyl, methoxybenzyl, nitrobenzyl, phenacyl, trichloroethyl trimethylsilyl, benzhydryl, phthalimidomethyl, phenyl, methoxyphenyl and succinimidomethyl.

5. A process as defined in claim 1 wherein the acyl group in the 7-position is an acyl group selected from the group consisting of (1) an acyl group having the formula

65 wherein n is zero or an integer from 1 to 6 and R_6 is selected from the group consisting of monocyclic carbocyclic and bicyclic carbocyclic aryl containing 6-14 carbon atoms cycloalkyl containing 4-8 carbon atoms and heterocyclic groups wherein the hetero atom is selected from the group consisting of O, S, N and combinations thereof, and substituted derivatives thereof wherein the substituent is selected from the group consisting of C_1 - C_3 alkyl, C_1 - C_3 alkoxy, cyano, nitro, hydroxy, halogen, trifluoromethyl,

17

carboxy, amino, C₁–C₄ carboxy alkyl and C₁–C₄ carboxyamido alkyl; (2) an acyl group having the formula

wherein R₇ is selected from the group consisting of C₁ to C₈ alkyl, C₂ to C₈ alkenyl and substituted derivatives thereof wherein the substituent is selected from the group consisting of amino, cyano, nitro, hydroxy, halogen, carboxy and carboxamido; (3) an acyl group having the formula

wherein n has the meaning set forth above, m is zero or an integer from 1 to 5, X is O or S and R₈ is selected from the group consisting of R₆, C₂ to C₈ alkenyl and substituted C₂ to C₈ alkenyl derivatives wherein the substituent is selected from the group consisting of amino, cyano, nitro, hydroxy, halogen, carboxy and carboxamido; (4) an acyl group having the formula

wherein R₆ has the meaning defined above and Y is selected from the group consisting of amino, protected amino, hydroxy, C₁ to C₃ alkoxy, carboxyl, and C₁ to C₃ alkanoxyloxy; and (5) phenyl-a,a-dimethylacetyl and substituted derivatives thereof wherein the substituent is selected from the group consisting of C₁–C₃ alkyl, C₁–C₃ alkoxy, cyano, nitro, hydroxy, halogen, trifluoromethyl, carboxy, amino, C₁–C₄ carboxy alkyl and C₁–C₄ carboxyamido alkyl.

6. A process as defined in claim 1 wherein the reaction is carried out at a temperature within the range of -10 to 100° C.

7. A compound of the formula

18

wherein R₁ is a heterocyclic group selected from the group consisting of dioxanyl, furyl, imidazolyl, isoxazolyl, morpholinyl, oxazolyl, pyranyl, pyrazinyl, pyrazolyl, pyridyl, pyrimidyl, pyrrolyl, thiazolyl, thiienyl, benzothienyl, triazinyl, triazolyl, tetrahydrafuryl, imazolinyl, imidazolidyl, piperidyl, tetrahydropyrimidyl, pyrrolidyl, and heterocyclic groups as set forth above which are substituted by one or more of the groups selected from the group consisting of C₁ to C₃ alkyl, C₁ to C₃ alkoxy, a cyano group, a nitro group, a hydroxy group, halogen, a trifluoromethyl group, a carboxy group, an amino group, a C₁ to C₄ carboxyalkyl group and a C₁ to C₄ carboxamidoalkyl group; n is zero or an integer from 1 to 5; and R₃ is C₁ to C₃ alkylene and m is zero or an integer from 1 to 3, and pharmaceutically acceptable cationic salts thereof.

8. A compound of the formula

wherein R₁ is C₁ to C₅ alkylene and m is zero or an integer from 1 to 3, and pharmaceutically acceptable cationic salts thereof.

9. 7 - (2' - thiienylacetamido) - 3 - cyclobutylcarbonyloxymethyl- Δ^3 -cephem-4-carboxylic acid.
